UNITED STATES PATENT OFFICE.

ENOCH OSGOOD, OF BANGOR, MAINE.

FASTENING LEATHER BELTINGS.

Specification of Letters Patent No. 9,710, dated May 10, 1853.

To all whom it may concern:

Be it known that I, ENOCH Osgood, of Bangor, county of Penobscot, and State of Maine, have invented a Mode of Fastening the Edges of Leather for Machine-Belting and other Purposes.

By means of this invention I am enabled to shorten, tighten or loosen machine belting at pleasure.

10 The nature of my invention is such that by the employment of metallic hooks and eyes on tapering screws inserted into the edges of leather belting the same may be closely united and made to run smoothly.

15 To enable others to make and use my invention I will describe the construction as follows: The edges of the leather are cut square off, for the purpose of receiving a tapering metallic screw. The screws have

20 either an eye or a hook at the top end (Fig-

ures 1 and 2.) The hook to unite with the eye. (Fig. 3). The screws having eyes are inserted into the edge of the leather on one end of the belt to be united, and those having hooks to be inserted into the edges of the 25 other end, opposite the eyes, for the purpose of uniting the two ends by placing the hooks within the eyes.

What I claim as my invention and desire to secure by Letters Patent, is—

30 Application of the tapering screws with hooks and eye screwed into the edges or ends of leather or belting for the purpose of uniting the edges together as above described.

ENOCH OSGOOD.
